COVER FOR A HOUSEHOLD ROTISSERIE

Bess Kaye, New York, N. Y.

Application May 26, 1955, Serial No. 36,226

Term of patent 3½ years

(Cl. D58—2)

Fig. 1 is a front perspective view of a cover for a household rotisserie embodying my new design; and

Fig. 2 is a rear perspective view thereof in inverted position.

The characteristic feature of my design for the cover disclosed resides in the pattern represented in full lines on the side thereof as shown.

I claim:

The ornamental design for a cover for a household rotisserie, as shown and described.
